UNITED STATES PATENT OFFICE

MAX KAPPNER, OF CINCINNATI, OHIO

ARCH SUPPORT ADJUSTER

Application filed July 3, 1929. Serial No. 375,835.

My invention relates to improvements in devices for altering the configuration of arch supports and is particularly adapted for use in connection with arch supports for the 5 human foot made in accordance with the teachings of Letters Patent of the United States 1,395,498 issued to me November 1, 1921.

It will be understood that malformations 10 of the foot vary so greatly that each foot fitted is apt to present an individual problem requiring some special change of the configuration of the metal portion of the support. The purpose of my present invention is to 15 provide a device capable of making all kinds of such changes and to a slight or substantial degree as the particular foot to be fitted requires.

Another object of my invention is to enable greater pressure to be brought upon the forward or rearward or upon the inside or outside of the support as needed, instead of a uniform pressure. Therefore, I provide 20 means for adjusting the position of the pressure block so as to secure such special pressure or pressures instead of the uniform pressure.

Another object of my invention is to provide a device in which the lever in either using 25 or non-using position is completely out of the way, where it will not interfere with those passing the bench to which the device is secured. Devices for this general purpose heretofore made have been so generally protruding from the bench as to be likely to 30 injure those passing or be itself broken off.

Another object of my invention is to provide an anvil table top on the device which together with the pressure block provides 35 means for making every change or alteration necessary to be made on an arch support.

I also provide a specially formed hammer for taking care of all the various uses to 40 which the device is to be put, aside from the changes made by pressure delivered through the pressure block.

In the particular embodiment of my invention selected for illustration:

Figure 1 is a vertical section through the

device, the device being shown secured to a working bench,

Fig. 2 is a top plan view of the device,

Fig. 3 is a side elevation of the device,

Fig. 4 is a plan view of a perfect arch support adapted to conform to the curvature of every bone in the foot, and

Fig. 5 is a view of my specially formed hammer.

Referring now to the drawings and particularly Figs. 1, 2 and 3, the device is secured to any suitable work table or bench 6 by means of screws 7 or in any other suitable manner. The double arm vise 8 is secured between the base 9 and anvil table top 10 by means of thumb screws 11, the vise member being free to reciprocate on the base 9. A rod 12 threaded at both its ends is secured at one end 13 to the anvil table top and at its other end 14 has a stop nut 15 outside the vise member 8. A spring 16 surrounding the rod 12 tends to normally maintain the vise in open position as shown in Fig. 3. An operating handle 17 is pivoted at one end 18 to the vise member 8, and on this end has a cam face 19 adapted to bear against the lower portion of the anvil table top to close the vise. A boss or stop 32 is provided on the handle 17 to limit the rotation of the handle so that it will not contact 70 with the bench or table to which the device is secured.

A metal pressure block 20 suitably cushioned is adapted to have its position regulated by thumb set screws 21, 22, 23 and 24. 85 The pressure block 20 may be made as a single piece or may be split centrally or otherwise so as to have pressure exerted in more varied directions. The anvil table top 10 is provided on its top surface with an embossment 25 centrally depressed in which the arch may be adjusted to conform to the particular curvatures of the cuboid and scaphoid bones of the foot. The table top is also provided with another embossment 26 90 also centrally depressed in which the arch may be adjusted to conform to the curvature of the metatarsal bones. The table top is provided with apertures 27 and 28 upon which the spur of the arch is placed so as not 95 100

to injure the spur in lowering the arch. A rounded flange 29 on the anvil table top is provided with a vertical aperture 30 through which rivets may be driven out of the arch support and the longitudinal aperture 31 is provided therethrough so that the rivets may be taken out of the flange.

In order to change the configuration and curvature of the arch 33, it is placed between the pressure block and the face 34 of the anvil table top with the metal portion of the arch in contact with the pressure block. The face 34 is formed to prevent flattening of the metatarsal portion of the arch support when pressure is applied. Any of the set screws 21, 22, 23 and 24 are then adjusted as desired, and the operating handle 17 is raised to whatever height is desired in order to bring pressure upon the arch 33 to increase the curvature of the arch support. When the handle 17 is in its extreme upper position it becomes locked there due to the then position of the cam 19 as shown in Fig. 1.

In order to flatten or lessen the curvature of the arch 33, it is laid upon the anvil table top with the spur 36 over one of the apertures 27 or 28 and the hammer 37 is used to apply whatever force is necessary to lower the arch support. This hammer 37 has any suitable handle 38 and has a metal tube member 39 to rigidly secure the raw hide heads 40 and 41 to the handle, the head 40 being flat and the head 41 being rounded. In order to change the curvature of the flange 42 of the arch support to conform to the particular curvature of the scaphoid bone and in-step, the flange is laid upon the rounded flange 29 on the anvil table top with the metal portion up and the flat end 41 of the hammer is used to change the curvature of the flange 42. If it is desired to remove a rivet from the arch support, the rivet is laid over the aperture 30 and removed by tapping the rivet with the hammer 37 and any suitable punch. In order to change the arch support to conform to the curvature of the metatarsal, the arch support is laid over the embossment 26 and the rounded end 41 of the hammer used to give the necessary pressure. If the arch support is to be changed to conform to the curvature of the cuboid and scaphoid bones, it is laid upon the embossment 25 and the rounded end of the hammer used to make the change.

55 I claim as my invention and desire to secure by Letters Patent of the United States:

1. In a device of the class described, the combination of a supporting base, an anvil table secured to said base, a vise member slideable between a portion of said anvil table and said base and guided theron, means for moving said vise member, a pressure block secured to said member and a plurality of means for changing the position of said block in relation to said member.

2. In a device of the class described, the combination of a supporting base, a vise member movable on said base, means for moving said member, means tending to maintain said vise member in open position, means for locking said member in closed position, a pressure block adjustably secured to said member, and means for making a plurality of adjustments of said block in relation to said member.

3. In a device of the class described, the combination of a supporting base, a vise member movable on said base, a lever pivoted to said vise member, means on said lever having a wedging action to move said vise member, a pressure block adjustably secured to said member, and a plurality of means for making a plurality of adjustments of said block in relation to said member.

4. In a device of the class described, the combination of a supporting base, an anvil table secured to said base, a vise member slideable between a portion of said anvil table and said base and guided theron, a lever pivoted at one end to said vise member, a cam surface on the pivoted end of said lever bearing against said anvil table to move said vise member, a pressure block secured to said member and a plurality of means for changing the position of said block in relation to said member.

5. In a device of the class described, the combination of a supporting base, a vise member movable on said base, means for moving said member, means tending to maintain said vise member in open position, means for locking said member in closed position, a pressure block adjustably secured to said member, and means for moving said block in a plurality of directions in relation to said member.

6. In a device of the class described, the combination of a supporting base, a vise member movable on said base, a lever pivoted to said vise member, means on said lever having a wedging action to move said vise member, said lever adapted to be substantially at right angles to said base in both extreme positions, a pressure block adjustably secured to said member, and means for making a plurality of adjustments of said block in relation to said member.

7. In a device of the class described, the combination of a supporting base, a vise member movable on said base, means tending to maintain said vise member in open position, means for closing said vise member, a pressure block adjustably secured to said member, and means for moving said block in a plurality of directions in relation to said member.

8. In a device of the class described, the combination of a supporting base, a vise member movable on said base, means tending to maintain said vise member in open

position, a lever and cam for closing said vise member, a pressure block adjustably secured to said member, and means for moving said block in a plurality of directions in relation 5 to said member.

9. In a device of the class described, the combination of a supporting base, a vise member movable on said base, means tending to maintain said vise member in open position, a lever and cam for closing said vise member, a pressure block adjustably secured to said member, and means for moving said block in a plurality of directions in relation 10 to said member, said lever adapted to be substantially at right angles to said base in both extreme positions.

10. In a device of the class described, the combination of a supporting base, a vise member movable on said base, means for 20 moving said member, means tending to maintain said vise member in open position, a pressure block adjustably secured to said member, and means for making a plurality of adjustments of said block in relation to said 25 member.

11. In a device of the class described, the combination of a supporting base, a vise member movable on said base, means for closing said vise member, a pressure block 30 adjustably secured to said member, a rod secured to said vise member and said pressure block, and a spring surrounding said rod and compressed between said member and said pressure block tending to maintain said vise 35 in open position.

12. In a device of the class described, the combination of a supporting base, a vise member movable on said base, a pressure block adjustably secured to said member, and 40 means for changing the position of the block vertically and horizontally in relation to said member.

In testimony whereof I have hereunto set
my hand.

45 MAX KAPPNER.
